UNITED STATES PATENT OFFICE.

CHARLES H. HUTCHISON, OF KNOXVILLE, TENNESSEE.

MULTIPLE-CHUTE COAL AND SLATE SEPARATOR.

Application filed August 19, 1924. Serial No. 732,997.

To all whom it may concern:

Be it known that CHARLES H. HUTCHISON, a citizen of the United States of America, residing at Knoxville, in the county of 5 Knox and State of Tennessee, has invented new and useful Improvements in Multiple-Chute Coal and Slate Separators, of which the following is a specification.

The present invention has for its purpose 10 to provide, in a multiple chute coal and slate separator, a construction and arrangement of a plurality of chutes in parallelism and superimposed, certain of which are reciprocable relative to others for grading the 15 coal into several sizes.

Another purpose is to provide means primarily for causing a separation of the slate as the coal is graded into several sizes.

It is well known that in some mines the 20 coal contains larger slate than is found in coal of other mines, therefore the present separator includes as still another purpose means for accommodating slate of various sizes during its separation from the coal.

A further purpose is the provision of 25 means for preventing clogging of the slate during its process of separating from the coal.

A still further purpose is to provide, in 30 a separator of this character, a chute which has an outlet at one end for the coal and outlets at the side for the slate, the reciprocable movement of the chute causing the coal proper to discharge from the outlet at 35 one end, the chute having a shell back or bottom, that is, a bottom which diverges toward the slate outlets to cause a separation of the slate from the coal proper during the reciprocable movements of the 40 chute, there being means at the side outlets to prevent clogging of the slate during its discharge.

It is also a purpose of the invention to 45 provide means, such as aprons, on the sides of the chutes for receiving the slate and discharging it upon a conveyer which conveys the slate from all of the separators to a unitary location.

It is to be understood that the particulars 50 herein given are in no way limitative and that, while still keeping within the scope of the invention, any desired modifications of detail and desired proportions may be made in the apparatus according to the circumstances.

The invention comprises further features

and combinations of parts to be hereinafter set forth, shown in the drawings and claimed.

In the drawings: 60
Figure 1 is a view in perspective of the improved multiple chute coal and slate separator constructed in accordance with the invention.

Figure 2 is a sectional view on line 2—2 65 of Figure 1.

Figure 3 is a sectional view on line 3—3 70 of Figure 1, showing the means for reciprocating the chutes and for operating the means for preventing clogging of the slate. 70

Figure 4 is an enlarged detail sectional view through one of the units of the multiple chute separator, showing one chute superimposed above the other and more clearly showing the adjustable means for restricting the side outlets for the slate. 75

Figure 5 is a transverse cross-sectional view of one of the chutes disclosed in Figure 4.

Referring to the drawings, 1 and 2 designate coal chutes, the former extending into and overlying the latter and adapted to receive coal in the condition in which it is procured from the mine. The upper end of the chute 1 has discharge openings 3, there being a discharge spout 4, it being the purpose for particles of coal from two inches and smaller to pass through the openings 3. The coal in the chute 1 delivers therefrom into the chute 2, so that lumps of coal 90 from two to four inches may pass through the openings 5 which are formed in the bottom of the chute 2, there being a discharge spout 6 for the passage of the coal. The coal from two inches and smaller and from two to four inches, which discharges from the spouts 4 and 6, delivers into the chutes 7 and 8 while coal and slate from four inches up discharge from the end 9 of the chute 2 into a chute 10. 95

The chutes 1 and 2 are suspended upon oscillatory hangers 11 and 12 which are respectively reinforced by the braces 13 and 14. The hangers are fulcrumed upon suitable shafts 15 adapted to be mounted in suitable bearings (not shown) above the separator. Suitable shafts 16 and 17 are mounted in bearings of the chutes 1 and 2 and in bearings of the lower ends of the hangers 11 and 12. Extending transversely below and at one end of the chute 1 is a shaft 18 driven by the belt 19 and pulley 100 105 110

20, and operating upon the shaft are eccentrics 21 and 22 which operatively connect with the chutes 1 and 2 by means of the pitmen 23 and 24 for the purpose of 5 imparting reciprocable movements to the chutes. The chutes 1 and 2, due to their operative connections with the shaft 18, reciprocate in opposite directions and it will be noted that these chutes at all times 10 remain overlapped, so as to prevent the loss of coal at the point where they overlap.

In order to further grade the coal into 15 various sizes and to separate the particles of slate therefrom, unit separators 25, 26 and 27 are provided. The unit separator 25 comprises the upper and lower chutes 28 and 29, the unit separator 26 comprises the upper and lower chutes 30 and 31, while the unit separator 27 consists of the upper and lower 20 chutes 32 and 33. The chutes 7, 8 and 10 respectively include sizing screens 34, 35 and 36 which extend at angles to the chutes 7, 8 and 10 which have solid bottoms. The sizing screens have spaced parallel rods 37, 25 it being obvious that the rods of the sizing screen 34 are spaced closer together than the rods of the sizing screen 35 which are, in turn, closer together than the rods of the sizing screen 36 which permits 30 coal of different sizes to be obtained. In fact, coal from one inch and below passes through the sizing screen 34 and enters the chute 28, and coal from two to three inches passes through the sizing screen 35 and is 35 received in the chute 30, while coal from three to six inches passes through sizing screen 36 and is received in the chute 32.

The chutes 28, 30 and 32 have discharge 40 spouts 38, 39 and 40 which convey coal to the chutes 29, 31 and 33. In fact, coal from one to two inches passes over the sizing screen 34 and then into the chute 29 by way of the discharge spout 38, the coal from three to four inches passes over the sizing screen 36 45 and into the discharge spout 39 which delivers the coal from three to four inches into the chute 31, while coal from six inches up passes over the bars of the sizing screen 36 and into the chute 33 by way of the spout 50 40. It will be noted that in separating and sizing the coal in this manner, it is possible to eliminate practically all of the slate from the coal. The sizing screens 34, 35 and 36 are supported respectively over the chutes 55 28, 30 and 32 due to their sides being rigidly fastened to the sides of said chutes 28, 30 and 32.

Extending at right angles to the chutes 60 28, 30 and 32 at certain of their corresponding ends and driven by a belt 41 and a pulley 42 is a shaft 43. Rotatable with the shaft are eccentrics 44, 45 and 46 respectively operatively connected by means of the pitmen 47, 48 and 49 and the shafts 50 to 65 the chutes 33, 31 and 29 which are suspend-

ed upon hangers 51 which are similar to the hangers 11 and 12. Also mounted upon and operable with the shaft 43 are eccentrics 52, 53 and 54 which are also, in turn, operatively connected to the chutes 32, 30 and 28 by 70 means of the pitmen 55, 56 and 57 and the shafts 58. The chutes 28, 30 and 32 are suspended on hangers 59 which are similar to the hangers 11, 12 and 51.

It will be noted that the construction and arrangement of the eccentrics on the shaft 43 are such as to impart opposite reciprocable movements to the chutes 28, 29, 30, 31, 32 and 33. In this way, the chutes receive 80 opposite shaking movements which cause the coal to discharge from the discharge ends 60, 61, 62, 63, 64 and 65.

The sides of the chutes 28 to 33, inclusive, have elongated slots 66 which are restricted by the adjustable slides or closures 67 which are mounted for adjustment due to their slot and bolt connections 68 with the sides of the respective chutes 28 to 33, inclusive. The slots 66 of the chute 28 are restricted less than the slots of the chute 29, the slots 66 of the chute 30 are regulated to permit larger slate particles to pass than are capable of passing through the slots 66 of the chute 28 while the slots 66 of the chute 31 are restricted less than the slots of the chute 30 but permit slate of larger size than may pass through the slots 66 of the chute 29. The slots 66 of the chute 32 are restricted less than the slots 66 of the chute 33 and permit larger slate particles to pass than may pass through the slots 66 of the chute 30, while the slots 66 of the chute 33 permit the passage of slate larger than is capable of passing through the slots of the chute 31.

In order to direct the slate particles of the coal toward the slots of the respective chutes 28 to 33, said chutes are provided with what are known as shell backs or bottoms 69. In other words, the bottoms of the chutes 28 to 33, inclusive, for the greater part of their length are raised centrally, therefore consist of diverging portions 70 which incline toward the slots in the sides of the chutes which direct the relatively flat portions of the slate toward and through the slots.

The opposite sides of the chutes 28 to 33, inclusive, have laterally extending aprons 71, those of the upper chutes 28, 30 and 32 being substantially directly over those of the lower chutes 29, 31 and 33. However, the upper aprons are relatively shorter than the lower aprons so that, during the reciprocable movements of the upper chutes, the slate passes from the upper aprons to the lower aprons which, in turn, deliver upon a conveyer belt 72 which is disposed and travels transversely of the chutes, whereby the slate may be conveyed to a unitary dump. The conveyer belt 72 operates through a trough 73 which prevents accidental loss of 130

the slate during its passage to the dump. Corresponding end portions of the chutes 29, 31 and 33 have trap doors 74 to be used when loading mine run coal. However, ordinarily the coal discharges from the ends 5 61, 63 and 65.

The opposite sides of the upper and lower chutes of each unit separator have parallel guide rods 75 and 76 fixedly mounted in 10 the supporting flanges 77 and mounted to reciprocate upon the guide rods 75 and 76 are perpendicular parallel bars 78 which are relatively reinforced by the braces 79. The lower ends of the bars 78 terminate in 15 dogs 80 which partly enter the slots 66 and constitute means to prevent clogging of the slate in the slots. Rising from the sides of the lower chutes 29, 31 and 33 of each of the units are upstanding arms 81 20 which are connected by the links 82 to the dog carrying bars 78 of the chutes 28, 30 and 32 so that when the lower chutes move in one direction the dog carrying bars 78 correspondingly move while the upper 25 chutes 28, 30 and 32 move in the opposite direction.

Depending from the sides of the chutes 28, 30 and 32 are arms 83 which are connected by the links 84 to the dog carrying bars 78 of the lower chutes 29, 31 and 33 so that, when the upper chutes 28, 30 and 32 move in one direction, the dog carrying bars of the lower chutes 29, 31 and 33 correspondingly move, while the chutes 29, 35 31 and 33 move in the opposite direction. In this manner, the slate, as it is passing through the slots in the sides of the chutes, is kept agitated, thereby preventing clogging and in many instances causing the slate 40 to break so as to insure prevention of clogging and the removal of practically all the slate from the coal. In some localities, the coal lumps are of various sizes and shapes; some lumps are cubical, some small and 45 some large, and at times there is considerable slate and flat pieces of coal, some small and some large. This mixture is deposited upon the coal chutes 1 and 2. The relatively small particles, flat or cubical or otherwise 50 shaped, pass through the discharge openings 3 and then through the spout 4 and fall upon the chutes 7. The next larger pieces of coal, either cubical or flat or otherwise 55 shaped, pass through the larger openings 5 of the chute 2 and then through the spout 6 and deposit on the chute 8. The relatively large pieces of coal of cubical contour and the large pieces of slate or large flat pieces 60 of coal discharge from the end of the chute 2 into the chute 9. These three different grades or fractures of coal are shaken in the chute 2 and then traverse the inclined bars or rods 37 of the chutes 7, 8 and 9, the cubical lumps depositing through the 65 spouts 38, 39 and 40, the relatively flat parti-

cles pass between the bars or rods 37 and deposit upon the diverging shell backs or bottoms 69 of the chutes 28, 30 and 32 and feed laterally onto the upper aprons 71. The particles of coal that pass through the 70 spouts 38, 39 and 40 deposit in the lower chutes 29, 31 and 33 where they are agitated until they feed over the shell backs or bottoms 69 of the lower chutes 29, 31 and 33, some of the particles feeding laterally upon 75 the lower aprons 71. The particles of coal that pass over the shell backs or bottoms 69 of the upper chutes 28, 30 and 32 toward the open ends, pass out through the discharge ends 60, 62 and 64. The particles of 80 coal that pass over the shell backs or bottoms of the lower chutes 29, 31 and 33 in a direction toward the open ends of these chutes, discharge through the discharge openings 61, 63 and 65, that is, provided the 85 trap doors 74 are open. There is only one conveyor belt disclosed. However, there may be several of these belts so as to feed the coal from the different discharge openings. Most of the large pieces of slate and 90 relatively large flat pieces of coal feed over the shell back or bottom of the chute 33 and pass laterally out upon the lower aprons 71. The relatively small and intermediate flat pieces of slate and coal similarly separate 95 and pass out upon the lower aprons 71 carried by the chutes 29 and 31. In this way it will be noted how the coal is separated and discharged into various fractures 100 of coal and slate.

The invention having been set forth, what is claimed is:

1. In a separator, a multiple of separator units, each consisting of upper and lower chutes provided with means for separating the slate from the coal, unitary means for imparting opposite reciprocable movements to the chutes, means for delivering to the units coal to be separated, reciprocating means carried by the upper and lower chutes 105 and operatively and respectively connected thereto in order to receive reciprocating movements, thereby preventing clogging of the slate when separated, and means intermediate the coal delivering means and the upper chutes of the respective units, whereby the coal may receive a second step of separation.

2. In a coal and slate separator, a multiple of separator units each consisting of upper and lower chutes provided with slate receiving aprons, the bottom of each chute having means for separating the slate from the coal and discharging it upon the aprons, means for delivering to the units coal to be separated, means operatively connecting with the chutes for imparting opposite reciprocable movements thereto, reciprocating means carried by the upper and lower chutes and operatively and respectively con- 125 130

nected thereto in order to receive reciprocating movements, thereby preventing clogging of the slate as it passes onto the aprons, and means intermediate the coal delivering 5 means and the upper chutes of the respective units, whereby the coal may receive a second step of separation.

3. In a separator, a separator unit consisting of upper and lower chutes, the 10 former having a sizing screen to permit of a certain size of coal to pass to the upper chute which has an outlet spout to carry another size coal to the lower chute, unitary means for imparting opposite reciprocable 15 movements to the chutes, the bottoms of which have means for separating the slate from the coal, aprons carried by the chutes to receive the slate as it separates while the coal discharges from corresponding ends of 20 the chutes, means operatively connected to and receiving reciprocable movements from the lower chute and being operatively carried on the upper chute for preventing clogging of the slate as it separates, and means 25 carried by the lower chute and connected to and receiving reciprocable movements from the upper chute to prevent clogging of the slate as it separates from the coal in the lower chute.

30 4. In a separator, a separator unit consisting of upper and lower chutes with means for delivering respectively to the chutes coal and slate to be separated, the bottoms of the chutes provided with diverging surfaces for causing the separation of the slate from the coal which discharges from corresponding ends of the chutes, the sides of the chutes having slate receiving aprons with which the diverging surfaces connect, and means for imparting opposite reciprocable movements to the chutes.

35 5. In a separator, a separator unit consisting of upper and lower chutes with means for delivering respectively to the chutes coal and slate to be separated, the bottoms of the chutes provided with diverging surfaces for causing the separation of the slate from the coal which discharges from corresponding ends of the chutes, the 40 sides of the chutes having slate receiving aprons with which the diverging surfaces connect, means for imparting opposite recip-

55 rocable movements to the chutes, and means operated by the chutes for preventing clogging of the slate during its passage to the aprons.

6. In a separator, a separator unit consisting of upper and lower chutes provided with coal discharges at corresponding ends and including means for delivering coal of different sizes to the chutes, said chutes having shell backs consisting of diverging surfaces, the sides of the chutes having slots and provided with lateral aprons to receive the slate as it separates from the coal, means to 60 impart opposite reciprocable movements to the chutes, means operatively mounted upon the upper chute and in turn operatively connected to and receiving reciprocable 65 movements from the lower chute for preventing clogging of the slate in the slots of the upper chute, and means operatively mounted on the lower chute and connecting to and receiving reciprocable movements from the upper chute for preventing 70 clogging of the slate in the slots of the lower chute.

7. In a separator, a separator unit consisting of upper and lower chutes provided with coal discharges at corresponding ends 80 and including means for delivering coal of different sizes to the chutes, said chutes having shell backs consisting of diverging surfaces, the sides of the chutes having slots and provided with lateral aprons to receive 85 the slate as it separates from the coal, means to impart opposite reciprocable movements to the chutes, means operatively mounted upon the upper chute and in turn operatively connected to and receiving reciprocable movements from the lower chute for preventing clogging of the slate in the slots of the upper chute, means operatively mounted 90 on the lower chute and connecting to and receiving reciprocable movements from the upper chute for preventing clogging of the slate in the slots of the lower chute, and means for varying the size of the slots to accommodate slate of different 95 thicknesses.

100 In testimony whereof he affixes his signature.

CHARLES H. HUTCHISON.
